United States Patent Office.

JOHN MAGEE, OF CHELSEA, MASSACHUSETTS, ASSIGNOR TO MAGEE FURNACE COMPANY.

Letters Patent No. 80,194, dated July 21, 1868.

IMPROVEMENT IN COOKING-STOVES.

The Schedule referred to in these Letters Patent and making part of the same.

TO ALL WHOM IT MAY CONCERN:

Be it known that I, JOHN MAGEE, of Chelsea, in the county of Suffolk, and State of Massachusetts, have invented certain Improvements in Cooking-Stoves, of which the following is a full, clear, and exact description, reference being had to the accompanying drawings, making part of this specification, in which—

Figure 1 is a perspective view of a cooking-stove, with my improved warming-closet applied thereto.

Figure 2 is a longitudinal vertical section through the centre of the same.

Figure 3 is a transverse section on the line xx of fig. 2.

Figure 4 is a horizontal section on the line yy of fig. 2, representing only the warming-closet and oven.

The subject of my present application relates to certain improvements in cooking-stoves, already referred to in two other applications made by me simultaneously with this; and my invention consists in a warming-closet, situated under the hearth of a high-hearth stove, in which cooked articles of food are placed to be kept warm, ready for use.

To enable others skilled in the art to understand and use my invention, I will proceed to describe the manner in which I have carried it out:

In the said drawings, A is the hearth-plate of an ordinary high-hearth stove, beneath which is formed a compartment, to be used as a warming-closet, B, for keeping cooked articles of food warm after being removed from the oven or utensils belonging to the stove.

The bottom of the warming-closet consists of a lid, C, hinged or otherwise pivoted at a , said lid being swung open into the position shown in fig. 2, for convenience in removing ashes, &c., from the ash-pit D, and for better obtaining access, through the opening b , to the flues E F, under the oven. The closet B is provided with doors, e, for snugly closing its front, so as to exclude the surrounding air, and thereby prevent its cooling.

H is the register or damper, for regulating the supply of air to the fuel in the fire-box I. The oven G may, if desired, be provided with an auxiliary flue, J, the construction and object of which are minutely set forth in a separate application for the same, and made by me simultaneously with this.

Instead of the stationary hearth-plate forming the top of the warming-closet, the said plate, or a portion of it, may be pivoted, or otherwise hinged, so that it may be swung open, to more readily insert and remove the article of food to be kept warm; or the lid may be made to slide, or be removed entirely from the top of the warming-closet, and the doors e, in front thereof, may be dispensed with, and two plates, forming the top and front of the closet, may be hinged or pivoted together, the lid forming the top being connected with the back of the hearth, and the lower plate covering the front of the closet, swinging freely thereon. The front, also, of the closet may be made removable, or swing or slide open independently of the lid forming the top of the said closet.

Furthermore, the doors e may be dispensed with, and access to the warming-closet may be obtained by opening a door at one or both ends thereof, without departing from the spirit of my invention.

Claims.

What I claim as my invention, and desire to secure by Letters Patent, is—

A warming-closet, B, placed under the hearth of a high-hearth stove, substantially as and for the purpose set forth.

I also claim the warming-closet B, the top of which is provided with a movable lid or door, in the manner and for the purpose described.

JOHN MAGEE.
